UNITED STATES PATENT OFFICE

2,681,587

ACCORDION

**Hans Rappold, Trossingen, Germany, assignor to
Matth. Hohner A.-G., Trossingen, Germany, a
Joint-stock company of Germany**

Application January 19, 1951, Serial No. 206,806

2 Claims. (Cl. 84—376)

1

The invention relates to accordions of the type which comprises two casings combined with a bellows, and whereby at least one of the casings is formed by a bellows frame, a cover and a rear wall; a panel, usually made of wood or metal, being arranged within the casing, and reed blocks comprising valves being fastened underneath said panel. The valves are controlled by means of levers by a keyboard arranged in proximity of the rear wall, which keyboard may be a push button or piano-style keyboard.

The principal object of the invention is an advantageous arrangement of the treble keyboard.

According to the invention the arrangement is of such a nature that the end of the panel facing the rear wall of the casing reaches at least up to the bellows frame, and that the lower end of the keyboard is arranged in the space between the rear wall of the accordion casing and the said part of the panel.

Owing to the deep position of the lower end of the keyboard within the accordion casing, attained through said arrangement, the keyboard width is smaller than that of the accordions hitherto known, and the decrease in height has the advantage of easier and more convenient playing because of the shorter distance between the player's hands. In addition, the side of the accordion casing facing the player is less high and fits well to the player's body.

Another object of the present invention is the manner in which the room for the arrangement of the lower end of the keyboard or the mechanism for controlling the register slides is created. In one form of realisation of the invention the panel mounts from underneath the keyboard in a slanting line towards the front wall of the accordion casing. It may ascend uniformly until it reaches the front end of the accordion casing or it may form an angle with the portion carrying the reed blocks. In the latter case the portion of the panel arranged underneath the keyboard mounts in a slanting line up to the reed blocks, and that portion of the panel which carries the said reed blocks forms an angle with the slantingly ascending portion of the said panel.

The angular portion of the panel may also be so constructed that it forms a trough into which the lower end of the keyboard reaches down. This arrangement has the advantage that the keyboard can be made to reach especially deep into the accordion casing.

It is also possible according to the present in-

2

vention that the trough is formed by the angular portion of the panel arranged below the keyboard together with the lower end of the keyboard support, and with a further realisation of the invention the space to receive the lower end of the keyboard is formed by the panel alone.

Another object of the present invention is that the portion of the cover which overlays the reed block rows in the proximity of the accordion casing rear wall is at right, or nearly right angle to the keyboard surface.

The invention will be more easily understood from the accompanying drawing showing several forms of accordions according to the invention and in which:

Figures 1 to 5 are cross sectional views with Fig. 1 showing a type of panel ascending in a uniformly slanting line from the lowermost point up to the front end of the accordion casing;

Fig. 2 showing a panel initially mounting in a slanting line and forming an angle before reaching the reed blocks;

Figs. 3-5 showing three different trough-shaped types of the space in the panel into which the keyboard extends; and

Fig. 6 is a perspective view partly in section of the accordion with a piano-style keyboard of Figs. 4 and 5.

In a casing 1 of the treble keyboard of an accordion, reed blocks 2 are arranged in rows and mounted from underneath on the bottom of a panel 3.

The keyboard may be one with push-buttons 4 (Figs. 1-3) or one with piano-style keys 5 (Figs. 4 and 5), which control the air passages 8 of the reed blocks 2 in the conventional manner by means of the links 6 and the valves 7. The reed blocks 2 and the levers 6 actuating the valves 7 are overlaid by a cover 9 joining the keyboard. A bellows frame 10 carrying the bellows 11 is arranged at the lower edges of the casing 1.

According to the invention the end of the panel 3 facing the rear wall 12 of the accordion casing 1 reaches at least up to the bellows frame 10. The end may be mounted directly on the frame 10 (Figs. 1, 4 and 5), or fastened some distance above it (Fig. 2), or penetrate into it (Fig. 3).

In the arrangement according to Fig. 1 the panel 3 mounts in a continuously slanting line from the bellows frame 10 to the front wall 13 of the accordion casing 1. The keyboard support 14 rests on the panel 3, or on an intermediate block 15. The keyboard support 14 is held by a prop 16 glued between the rear of the said

keyboard support 14 and the rear wall 12 of the accordion casing 1.

In the arrangement according to Fig. 2 the panel 3 has an angular form. The panel 3 does not entirely reach up to the bellows frame 10 but leaves a small clearance 17 and is fastened to the rear wall 12 of the accordion casing 1.

At first the panel mounts in a slanting line and the portion 18 of the panel 3 carrying the reed blocks 2 is arranged at a certain angle to the slanting portion 19 of said panel, e. g. in such a way that said portion 18 runs parallel to the plane of the bellows frame 10.

The slanting portion 19 of the panel 3 is preferably reinforced because of the keyboard support 14, e. g. by a block 29 (shown by dotted lines) glued to the said portion from underneath.

Fig. 3 shows an arrangement of the invention according to which the space to receive the lower end of the keyboard is of a trough-like shape. In this arrangement of the invention the slanting portion of the panel 3 and the lower end of the keyboard support 14 form the trough 21. The angular portion extends deep enough to allow the trough 21 to penetrate into the bellows frame 10, whereby the levers 22 of the keyboard and the levers 6 controlling the valves 7 are mounted and jointed at the bottom of the trough.

In this arrangement the angular portion of the panel has the form of a right, or almost right angle 23, whose free end is glued to the lower end of the keyboard support 14, the latter being held by a prop 16 glued between said keyboard support 14 and rear wall 12 of the accordion casing 1.

The arrangement according to Fig. 4 also has a trough-like space 21 in which the lower end of the keyboard, formed in this case by the keys 5, is arranged. The said trough 21 is formed by the angular end of the panel 3 and by the rear wall of the accordion casing 1 which wall in this case serves as keyboard support. The end 24 of the angular portion 23 is fastened between rear wall 12 of accordion casing 1 and bellows frame 10.

The mechanism 38 for the register slides 25 which are controlled by the key 26 and the linkage 27 are preferably arranged in the trough.

Fig. 5 also shows a trough-shaped space 21 serving to receive the lower end of the keyboard. In this type the trough 21 is inside the bellows frame 10, and the keys are arranged as low as possible. The end of the angular portion 23 is U-shaped and its end portion 24 is fastened between the rear wall of accordion casing 1 and the bellows frame 10.

In all modes of realisation of the present invention the portion 29 of the cover 9, overlaying the reed block rows in the proximity of the rear wall 12 of the accordion casing 1, is at a right, or almost right angle to the keyboard surface.

What I claim is:

1. An accordion comprising two casings and a bellows connected with its ends to said casings, one of the casings comprising a bellows frame,

a rear wall and a front wall both mounted on said bellows frame, a cover, a panel arranged between the rear wall and the front wall within said cover, reed blocks arranged underneath said panel, a keyboard arranged in proximity of said rear wall with the rear end of the keyboard arranged between the rear wall and the reed blocks, said reed blocks including valves being adapted to be controlled by said keyboard, at least one part of said panel being arranged at an acute angle relative to the plane of the bellows frame, the end portion of the panel facing the rear wall being arranged to extend substantially to the plane of the bellows frame where the bellows is secured, the keyboard being arranged approximately perpendicularly to that part of the panel which is arranged at an acute angle relative to the plane of the bellows frame, and the part of the panel which is spaced the greatest distance from the keyboard being for the most part spaced from the plane of the bellows frame, a part of one of said casings on which the keyboard is supported having means which include pivots for the keys of the keyboard, and a trough comprising a part of the rear wall and an extension of the panel provided for receiving the lower end of the keyboard, the walls of said trough including the portion of the panel arranged under the keyboard and the lower end of said panel supporting the keyboard with the rear wall of the casing being integral with the said part of the rear wall forming a part of the trough.

2. An accordion according to claim 1, in which the rear end of the keyboard is arranged in said trough, and in which at least one register slide is provided between said reed blocks and said valves, a mechanism in the trough for controlling said register slide, a key for controlling said mechanism, and a linkage connecting said last-mentioned key with said mechanism.
